UNITED STATES PATENT OFFICE.

WALTER D. WRIGHT, OF DRYAD, WASHINGTON, ASSIGNOR OF ONE-HALF TO JOSEPH F. KOCH, OF TACOMA, WASHINGTON.

FILM-FIRE EXTINGUISHER.

Application filed March 10, 1922. Serial No. 542,542.

To all whom it may concern:

Be it known that I, WALTER D. WRIGHT, a citizen of the United States, residing at the town of Dryad, in the county of Lewis and State of Washington, have invented new and useful Improvements in Film-Fire Extinguishers, of which the following is a specification.

My invention relates to devices for extinguishing film fires within a moving picture projecting machine. The objects of my invention are, first, to promptly extinguish a film fire, either automatically or by the will of the motion picture machine operator before the fire can spread and cause the destruction of life and property, and second, to promptly extinguish a film fire within the motion picture projecting machine and thus prevent the destruction of the picture film and also prevent delay in the showing of the moving pictures.

I attain these objects by means of the mechanism illustrated in the accompanying drawings in which:—

Fig. 1 is a front view of my invention when set ready for use. Fig. 2 is a similar view of my invention showing the parts in operative position to extinguish a film fire. Fig. 3 is a cross section of Fig. 2 on line 3—3. Fig. 4 is a view of my fusible link; and Fig. 5 shows my invention attached to the film chamber to extinguish a fire therein.

Similar characters refer to similar parts in the several views.

My invention is designed to be contained within a suitable metal cabinet 1 made fire-proof by lining with asbestos or other suitable material, said cabinet having an outlet 2 connected with the film reel chamber 3. The hinged door 4 constitutes one side of the cabinet to permit access thereto.

The extinguishing apparatus comprises a container tank 5 with a tapered bottom and outlet 6 centered over the cabinet outlet 2. The outlet of the container is closed by means of a suitable disk stopper 7 held against the outlet opening 6 by an annular shaped end 8. The lever arm 9 which is actuated by the spring 10 holds the stopper 7 in place. An electric magnet 11 attached to the opposite end of the lever arm 9 is designed to release the stopper 7 and let the extinguishing liquid through the outlet 2 in the film reel chamber. The magnet 11 is magnetized by the wires 12 which are con-

tacted with a proper battery or circuit. A knife switch circuit breaker 13 when open, as in Fig. 1, leaves the magnet 11 inactive, but when closed as shown in Fig. 2, it then acts on the lever arm 9 and releases the stopper 7. The extinguishing liquid then flows freely into and through the cabinet outlet 2 and into the chamber 3.

The magnet 11 may be operated voluntarily by the operator through a switch 14 but automatically by the knife cutout switch 13 actuated by the spring 15, when released by a fusible link when a film fire occurs. For a fusible link I have adopted the novel idea of using a short piece of motion picture film 16, one end of which is attached to the wall of the cabinet by means of a V-shaped hook 17 and by a similar hook 18 to the knife of the circuit breaker 13 at the opposite end. The hooks 17 and 18 are inserted in the small holes at the sides of the moving picture film. It is to be observed the film of the fusible link is stretched directly over the discharge outlet 2 and the loose end 19 hangs down through the outlet 2 nearly in contact with the film reel chamber. A suitable stopper 20 closes the opening through which the container tank 5 is replenished.

The automatic operation of my invention as shown and described is very simple. Should a moving picture film break and be set on fire by the light rays of the moving picture projecting machine, the flame will quickly follow the film within the reel chamber 3 and on reaching the discharge opening 2 connected therewith will instantly set fire to the end 19 of the fusible link 16 and each will be destroyed. The knife switch now being released, the spring 15 will close it and the electric magnet 11 acting on the lever 9 will open the container tank 5. The extinguishing liquid will now flow into and through the discharge opening 2 into the reel chamber 3 and instantly extinguish the burning film therein, thus preventing further damage. The picture film can at once be reconnected and shown again without delay. The container tank 5 can at once be refilled with pyrine or other suitable extinguishing fluid through the stopper opening 20 after a new film fusible link is put in and the extinguisher is again ready for use.

It is to be observed the annular end 8 of the lever 9, when the disk stopper 7 is released, allows the extinguishing fluid to flow

2
directly into the discharge outlet 2. In the making of my invention, I do not limit myself to exact dimensions, proportions or materials, but reserve the right to vary the same as conditions and circumstances may require.

Having described my invention, I claim—

In a fire extinguishing device, a film cabinet having an outlet opening in its upper portion, fire extinguishing mechanism located above the film cabinet and having a discharge outlet in alignment with the opening in the film cabinet, said fire extinguishing mechanism comprising a cabinet, a liq-

uid container supported in said cabinet, a valve for controlling the efflux of liquid from said container, electrical means including an electro-magnet for opening and closing said valve, a switch for causing said electrical means to become operative when a fire occurs in said film cabinet and a length of fusible film material secured within said fire extinguisher cabinet and having one end extending through the opening in the film cabinet into the film cabinet.

WALTER D. WRIGHT.
